US00D690196S

(12) **United States Design Patent**
Kessler, Jr. et al.

(10) **Patent No.:** **US D690,196 S**
(45) **Date of Patent:** ** *Sep. 24, 2013

(54) **STURDY BASE FLEXIBLE CONTAINER
WITH RECTANGULAR FLAT BASE**

(71) Applicant: **Printpack Illinois, Inc.**, Elgin, IL (US)

(72) Inventors: **David James Kessler, Jr.**, Atlanta, GA (US); **Thomas P. Seidel**, Smyrna, GA (US)

(73) Assignee: **Printpack Illinois, Inc.**, Elgin, IL (US)

(*) Notice: This patent is subject to a terminal disclaimer.

(**) Term: **14 Years**

(21) Appl. No.: **29/437,778**

(22) Filed: **Nov. 20, 2012**

(51) **LOC (9) Cl.** **09-03**

(57) **CLAIM**

The ornamental design for a sturdy base flexible container with rectangular flat base, as shown and described.

DESCRIPTION

FIG. 1 is a front view of a sturdy base flexible container with rectangular flat base showing our new design;

FIG. 2 is a rear view thereof;

FIG. 3 is a first side view thereof;

FIG. 4 is a second side view thereof;

FIG. 5 is a top view thereof;

FIG. 6 is a bottom view thereof;

FIG. 7 is a forward upper perspective view thereof; and,

FIG. 8 is a forward lower perspective view thereof.

1 Claim, 3 Drawing Sheets
